INVENTOR
BY Victor J. Evans
and Co.

ATTORNEY

UNITED STATES PATENT OFFICE

HENRY A. ODENDAHL, OF LITTLE FALLS, NEW JERSEY

VAPORIZER

Application filed July 17, 1931. Serial No. 551,484.

This invention relates to vaporizers or mixing devices especially adapted for use on internal combustion engines and has for the primary object the provision of a device of the above stated character to be arranged in the path of the fuel from the carburetor to the engine for thoroughly mixing or breaking up the particles of fuel which fail to become vaporized by the carburetor and prior to entering the explosion chambers of the engine so that a more efficient operation of the engine may be had.

Another object of this invention is the provision of a fan shaped member rotatably mounted between the outlet of the carburetor and the intake manifold of the engine and rotated by the passing of the fuel and having the blades so pitched and serrated to cause thorough mixing of the fuel.

A further object of this invention is the provision of perforated elements carried by the blades of the fan shaped member and arranged angularly thereto for aiding in mixing the fuel.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a plan view illustrating a vaporizer or mixing device constructed in accordance with my invention.

Figure 2 is a sectional view taken on the line 2—2 of Figure 1.

Figure 3 is a sectional view taken on the line 3—3 of Figure 1.

Figure 4 is a plan view illustrating the mixing element prior to being formed into fan shape.

Referring in detail to the drawing, the numeral 1 indicates a supporting member in the form of a plate 2 having apertures 3 for receiving the fasteners between the outlet neck of a carburetor and the intake manifold of an engine. The plate 2 is provided with an opening 4 aligning with the outlet of the

carburetor and the passage of the intake manifold. A supporting bar 5 is formed on the plate 2 and traverses the opening 4 and carries a shaft 6 on which is journalled a mixing element 7. The mixing element 7 is constructed from a circular plate cut away to form segmental shaped portions which are bent or twisted to provide blades 8 having extensions 9 arranged at right angles to the blades. The edges of the blades 8 and extensions 9 are provided with serrations 10. The extensions 9 are provided with a plurality of apertures 11. The central portion of the plate is secured to a hub 12 journalled upon the axle 6.

The passage of fuel from the carburetor to the intake manifold will be through the opening 4 causing a rotation of the mixing element 7 and due to its fan shape and angularly disposed extensions 9 and serrated edges 10 will thorough mix or break up the fuel so that when the fuel enters the engine it will be in a highly combustible state.

Having thus described my invention, what I claim is:

A mixing device comprising a circular plate provided with a centrally located opening to receive a shaft and having cut-away portions forming segmental shaped portions bent to form blades and said segmental shaped portions having their curved edges serrated, each of the segmental shaped portions being arcuately severed adjacent the opening and bent angularly to form an extension to each blade and having perforations therein and provided with serrations in the free edges thereof, said extensions having the adjacent ends thereof substantially interengaged and disposed over the opening and spaced therefrom and from the shaft, and a hub secured to the plate and journalled on the shaft.

In testimony whereof I affix my signature.

HENRY A. ODENDAHL.
